CLAIM

I claim the ornamental design for a T-bar strap mounted calf feeder, as shown and described.

DESCRIPTION

FIG. 1 is a front perspective view of a T-bar strap mounted calf feeder in accordance with my new design, shown in a retracted configuration;

FIG. 2 is a rear perspective view thereof;

FIG. 3 is an enlarged front view thereof;

FIG. 4 is an enlarged rear view thereof;

FIG. 5 is a side view of the T-bar strap mounted calf feeder, the opposite side being a mirror image thereof;

FIG. 6 is a top view of the T-bar strap mounted calf feeder, the bottom view being a mirror image thereof;

FIG. 7 is a front perspective view of the T-bar strap mounted calf feeder, shown in a first extended configuration;

FIG. 8 is a rear perspective view thereof;

FIG. 9 is a side view of the T-bar strap mounted calf feeder, shown in a second extended configuration, the opposite side being a mirror image thereof; and,

FIG. 10 is a top view thereof, the bottom view being a mirror image thereof.
